CLAIM

The ornamental design for a display screen or portion thereof with graphical user interface, as shown and described.

DESCRIPTION

FIG. 1 is a front view of a display screen or portion thereof with a graphical user interface, with a bounding shape surrounding a section thereof and a number corresponding to a detailed view of the corresponding section, showing our new design.

FIG. 2 is a detailed front view of the section surrounded by the bounding shape of the display screen or portion thereof with the graphical user interface of FIG. 1, showing our new design.

FIG. 3 is a front view of a display screen or portion thereof with graphical user interface, with a bounding shape surrounding a section thereof and a number corresponding to a detailed view of the corresponding section, showing our new design.

FIG. 4 is a detailed front view of the section surrounded by the bounding shape of the display screen or portion thereof with the graphical user interface of FIG. 3, showing our new design.

FIG. 5 is a front view of a display screen or portion thereof with graphical user interface, with a bounding shape surrounding a section thereof and a number corresponding to a detailed view of the corresponding section, showing our new design.

FIG. 6 is a detailed front view of the section surrounded by the bounding shape of the display screen or portion thereof with the graphical user interface of FIG. 5, showing our new design.

FIG. 7 is a front view of a display screen or portion thereof with graphical user interface, with a bounding shape surrounding a section thereof and a number corresponding to a detailed view of the corresponding section, showing our new design; and,

FIG. 8 is a detailed front view of the section surrounded by the bounding shape of the display screen or portion thereof with the graphical user interface of FIG. 7, showing our new design.

The outermost broken lines in FIGS. 1, 3, 5 and 7 illustrate a display screen or portion thereof and form no part of the claimed design. The broken lines with alternating long and short segments indicate bounding shapes of FIGS. 1, 3, 5 and 7 that are illustrated as enlarged detailed views in FIGS. 2, 4, 6, and 8, respectively. The remaining broken lines illustrate portions of the graphical user interface that form no part of the claimed design.

FIG. I

FIG. 2

FIG.3

FIG. 4

FIG.5

FIG. 6

FIG. 7

FIG. 8
